UNITED STATES PATENT OFFICE.

JOHN NELSON, OF OTTAWA, KANSAS.

AIRSHIP.

1,366,584.

Specification of Letters Patent. Patented Jan. 25, 1921.

Application filed July 17, 1919. Serial No. 311,464.

To all whom it may concern:

Be it known that I, JOHN NELSON, a citizen of the United States of America, residing at Ottawa, in the county of Franklin 5 and State of Kansas, have invented certain new and useful Improvements in Airships, of which the following is a specification.

The primary object of my invention is the provision of an air ship adapted to elevate without the employment of wings or propellers and to descend whenever desired, such operations being entirely at the will of the pilot incurring only the expense of air exhausting means and vacuum control.

15 A further object of the invention is to provide an air ship having a chamber for providing elevating and lowering means for the craft, while the travel through the air is controlled by motor driven means, the steering 20 of the craft being easily effected.

A still further object of the invention is to provide an air craft having a hull adapted for elevating the craft to a suitable height through the air, a cabin supported by the 25 hull having motor driven means for causing the craft to travel under the control of steering mechanism, adjustable folding wings or aerofoils carried by the hull serving as sustaining planes and parachute members 30 while sailing and descending.

With these general objects in view, my invention will now be fully described in connection with the accompanying drawings and in which like reference characters designate 35 corresponding parts throughout the several views.

In the drawings,

Figure 1 is a side elevation of the invention positioned upon the ground,

40 Fig. 2 is a top plan view thereof,

Fig. 3 is a vertical, transverse, sectional view of the same,

Fig. 4 is a longitudinal detail sectional view 45 showing features of the wing operating means, and

Fig. 5 is an enlarged detail view, partly in section, of one of the wheel members.

Broadly considered, my invention comprises an inverted hull 10 having a keel 11 longitudinally at the top thereof, the said 50 hull being substantially of the form of the hull of a ship with a bow 12 and a stern 13. A car 14 depends from the bottom deck 15 of the hull 10 having posts 16 to which a 55 platform 17 is mounted beneath the deck

15. Shock absorbers 18 upon the lower ends of the posts 16 have wheels 19 for mounting upon the ground 20 when the craft is not in use and for service in launching and alighting.

Three-cylinder motors 21 are mounted at opposite sides of the platform 17 between the forward posts 16 having a common crank shaft 22 journaled through said post 16 at the bow of the ship, a propeller 23 65 upon each end of the shaft 22 being serviceable in moving the craft forwardly either when elevated in the air or lowered upon the ground 20. It will be evident that separate controls for the opposite propellers 23 70 may be employed in steering the craft and that a self-starter 24 of any desired form may be mounted upon the platform 17 with a pinion 25 for meshing with the gear 26 upon the shaft 22 and constituting the fly 75 wheel.

An air exhausting pump 27 communicates as at 28 with the interior of the hull 10 through the deck 15 thereof, a belt 29 serving to operatively connect said pump with the shaft 22 for service whenever desired in exhausting the air from the hull 10 to as near a perfect vacuum as possible. A vacuum gage 30 upon the deck 15 renders it easy to ascertain the conditions within the 85 hull 10. This hull is preferably formed of sheet aluminum having suitable strengthening stays or ribs 31 of steel or suitable metal, it being understood that similar strengthening means may be provided either exteriorly or interiorly of the hull 10 while a heat insulator such as asbestos may also be provided, if desired.

An air inlet valve 32 through the deck 15 is controlled by a rod 33, it being understood that whenever it is desired to elevate the air craft, the pump 27 is operated, forming a vacuum within the hull 10 whereby the surrounding air and the air beneath the hull buoys the same upwardly in the same 100 manner that a submarine is caused to rise through the water when submerged by exhausting the water from the submarine. After the ship has reached the desired elevation, the propellers 23 will be operated 105 for causing the ship to travel through the air. Upon pushing the rod 33 to shift the plate 34 of the valve 32 to its open position, air will enter the hull 10 causing the air craft to descend. Any suitable means such 110

as a clutch 35 permits the turning of the shaft 22 without revolving the propellers 23 while a loose pulley 36 for the belt 29 permits the pump 27 to be active or idle at will.

5 The pilot upon the seat 37 carried by the platform 17 controls the motors 21, propellers 23 and pump 27 at will and by forming the vacuum in the hull 10 by operating said pump 27, the air craft is caused 19 to rise to the desired elevation, the said hull having sufficient strength to withstand the air pressure from without.

An inflating valve 38 is provided for the hull 10 whereby suitable gas may fill the hull after the usual manner of a gas bag and at which times, the rod 33 would serve to permit the gas to escape from the hull 10 which would fill with air causing the descent of the air ship.

20 An empennage 39 consists of a rudder 40 carried by a ball 41 in a socket 42 centrally of the stern 13. This rudder is of double formation having horizontal fins 43 and vertical fins 44 and operable for movement 25 upon the ball joint 41, 42 by the rods 45 as a vertical rudder and by the rods 46 as a horizontal rudder. Pull cords 47 attached to the rods 45 pass over pulleys or similar means 48 and extend to a convenient point 30 for operation by the pilot in any manner desired, such as by a steering wheel 49. The rods 45 are adapted to slide within slots 50 of the socket 42 and whereby it will be evident that the craft may be easily steered laterally by the shifting of the rudder 40 35 through the agency of said wheel 49. In a similar manner, cords 51 are carried by the rods 46 and extend to points adjacent the driver's seat 37 for convenience in steering the craft upwardly and downwardly.

40 Folding wings or aerofoils 52 are formed of such material as canvas having their inner edges 53 secured at opposite sides of the craft beneath ledges formed by recesses 54 in the bottom of the hull 10. These wings 52 have a plurality of ribs 55 pivoted at points 56 beneath the ledges 54 adjacent the forward end of the hull and whereby it will be evident that the wings 52 may be folded inwardly substantially beneath the ledges 54 when not in use but may be projected outwardly at opposite sides of the craft for supporting the weight of the craft in the air whenever desired. Suitable folding braces 57 are provided between the ribs 55 and rods 58 pivoted as at 59 to the sides of the hull 10 are attached as at 60 at suitable points upon the wings 52 for assisting in maintaining the wings horizontal when open, it being understood that any number of rods 28 may be used while additional strengthening means for the wings may also be employed if desired.

45 A suitably braced ledge 61 is provided 65 at each side of the bow 12 substantially in

alignment with the wings 52 when outstretched. Similarly arranged operating cords or chains 62 are secured as at 63 to the forward rib 55 of the wings 52, the said cords 62 passing over a pulley 64 beneath each ledge 61 and over pulleys 65 upon the deck 15 with the corresponding opposite ends of the cord 62 attached to a slide 66 upon a suitable support 67 beneath the deck 15. A drum 68 journaled adjacent the platform 17 has a flexible member or cord 69 wound around said drum with its opposite ends attached to the slide 66. A worm 70 upon a turn shaft 71 having a hand wheel 72 meshes with a pinion 73 for operating 80 the slide 66.

By turning the wheel 72 and moving the slide 66 in the required direction, the forwardmost ribs 55' of the wings 52 will be swung upon the pivots 56 either forwardly 85 for opening the wings or rearwardly for closing the same as desired. The worm 70 and gear 73 provide means in which the wings 52 are locked at any desired adjustment either open or closed or in partially 90 unfolded position, this being regulated during the operation of the air craft especially when desiring to descend. When the craft alights upon the ground such as 20, the propellers 23 are employed for moving 95 the craft into the hanger.

The complete operation of the invention having been fully described, the air ship may rise or descend at will as well as travel 100 through the air steered by the double rudder 40 and the manipulation of the clutches 35 for the propellers 23.

While the form of the invention herein shown and described is what is believed to be the preferable embodiment of the same, 105 it is nevertheless to be understood that minor changes may be made in the combination and arrangement of parts without departing from the spirit and scope of the same as claimed. When the air is exhausted from 110 the hull the ship rises in the air until it finds an altitude where the surrounding air pressure equals the pressure of the air that the hull of the air ship has displaced and compared with the lifting capacity of an air 115 ship using light air or gas, the same principle is employed that the heavier air surrounding the ship presses the ship upwardly together with its load to a level where the atmospheric pressure is equalized. 120

What I claim as new is:—

1. An air ship comprising an inverted hull, foldable wings secured beneath the lateral edges of the hull, ribs for said wings pivoted adjacent the forward end of the 125 hull, a slide centrally beneath the hull, an operating cord for each wing secured intermediate their ends to the forward rib of the wings, the opposite ends of the cords being attached to said slide whereby the wings 130

will be simultaneously opened or closed upon moving the slide longitudinally of the hull and operating means for said slide.

2. An air ship comprising an inverted hull, foldable wings secured beneath the lateral edges of the hull, ribs for said wings pivoted adjacent the forward end of the hull, a slide centrally beneath the hull, an operating cord for each wing secured intermediate their ends to the forward rib of the wings, the opposite ends of the cords being attached to said slide whereby the wings will be simultaneously opened or closed upon moving the slide longitudinally of the hull,
- 15 a drum journaled beneath the hull, a flexible member wound around said drum with its ends extending in opposite directions attached to opposite sides of said slide, spaced supporting pulleys for said flexible member,
- 20 a worm and pinion drive for said drum

adapted for self-locking the wings when adjusted and an operating wheel for said worm and pinion drive.

3. An air ship comprising a vacuum controlled hull having side eaves, flexible wings secured at one edge beneath said eaves, strengthening ribs for the wings and means associated with the forward strengthening rib for opening and closing the wings, said wings when folded being substantially disposed beneath said eaves.

3. An air ship comprising a vacuum controlled hull having side eaves, flexible wings secured at one edge beneath said eaves, strengthening ribs for the wings and means associated with the forward strengthening rib for opening and closing the wings, said wings when folded being substantially disposed beneath said eaves.
4. An air ship including a vacuum controlled hull, a car suspended therebeneath, flexible wings on the hull, strengthening ribs for the wings radiating from a single point, endless cords, each connected to the forward ribs of the wings and operable from the car to open and close the wings.

In testimony whereof I affix my signature.

JOHN NELSON.
